DERENDORF, GERMANY

OPERATING ELECTRIC PROJECTILE FUSES

Application filed August 1, 1927, Serial No. 209,847, and in Germany September 1, 1926.

Our invention relates to means for operating electric fuses for projectiles.

In electric projectile fuses the electric energy required for the ignition of the primer is already present in the projectile before the discharge, in an electric storage device, such as an accumulator or a condenser, or the projectile contains a current producing plant, such as a generator or a cell, which enters into action on or after the shot during the flight 10 of the projectile or only on its impact on the aim, and produces the required electric energy. The projectile thus carries with it already before the shot and in any condition, 15 the entire energy required to cause the explosion of the bursting charge. If this energy is not present there from the first in the condition required for the ignition, that means as electric energy, the latent energy is trans- 20 formed automatically after the shot into electric one, without that the operations further enacted and the effects resulting therefrom would permit any further human influence.

Now the method and the means forming the 25 subject-matter of our present invention provide the possibility of imparting to these operations an intentional and determined direction even after the projectile has been fired.

According to our invention the electric energy 30 required for initiating the ignition of the primer or for immediately igniting the latter, is transmitted only after the shot and during the flight of the projectile from a source of current separate from the projectile, 35 or only a portion of this required electric energy is transmitted to the igniting device during the flight of the projectile after the shot, whilst the projectile itself carries with it, already before being fired, the remaining 40 portion of the required energy in a latent state in a storage device, and transforms it into active power by means of a generator only during its further flight.

Furthermore, a very reliable guard for the 45 projectile, when still in the gun-barrel or on transport, is thus created, as before the shot till the moment the projectile leaves the muzzle of the barrel it possesses no energy that 50 would cause the explosion of the bursting

charge, or only so little energy, that a premature or unintentional ignition is excluded.

Finally, electric time fuses or delay action fuses may be set, according to our invention, so as to act at a determined moment, by the aid of the means the invention affords, without special operations being required as hitherto, which take up much time and disturb the desired succession of the shots.

To carry out the method forming the subject-matter of our invention, an electric conductor is arranged beside the path of the projectile, which conductor is conductively connected to a source of current and from which the electric igniting device of the projectile receives the required electric energy by a contact action, when passing past said conductor during the flight of the projectile. Or a field of lines of force is arranged beside the path of the projectile, which field produces an induction current in the electric igniting device of the projectile passing through said field after being fired. According to, whether a projectile fitted with an electric fuse is fired that possesses only an electric accumulator or besides the latter a power producing plant, the whole electric energy required for initiating the ignition of the primer or for immediately igniting the latter, is transmitted to the projectile, on only the remainder of energy still wanting.

Preferably that portion of the electric power producing plant serving to charge the electric fuse and arranged outside the projectile and causing a current to flow in the fuse or producing an induction current therein, that is, the contact points or an exciting coil, are arranged in front of the muzzle of the gun-barrel. The charging of the electric fuse thus takes place only after the projectile has already left the gun-barrel. This affords a very great safety of the fuse when still within the barrel. It is further obtained by this arrangement, that the charging of the fuse and the mechanical motions eventually tripped therein take place only after the projectile is not longer accelerated or is accelerated still in such a little degree only, that these motions of mechanical fuse members are not interfered with or prevented at all

by forces of inertia. The contact points or the members producing a field of lines of force, of the plant and arranged beside the path of the projectile are preferably rigidly connected with a part of the gun that partakes of the pointing motions of the latter, as for instance with the cradles or with the gun-barrel itself. These members then assume always the correct position relatively 5 to the projectile passing past them and to its electric fuse.

Furthermore, our invention affords suitable means for varying and differently regulating the current flowing in the conductor arranged near the path of the projectile, or the strength of the lines of force, in order to vary the energy to be supplied to the fuse or to be generated therein. This result may be obtained in a simple manner by inserting 15 a regulating resistance in the circuit comprising said contact points or said induction coil. This arrangement enables the gun to fire projectiles having electric fuses that require different quantities of electric energy for the 20 ignition of the primer of the bursting charge, as it permits of the current plant to be adapted to the different conditions and nature of the fuses. Besides, when projectiles are used 25 the setting to different ignition moments of the fuses of which is effected by varying the quantity of the electric energy supplied to them, the possibility is afforded of the fuses being set to different ignition moments by 30 simply varying said current or the strength 35 of said field of the electric plant arranged outside the projectile.

In order to allow of our invention to be more easily understood, a preferred embodiment of the means for carrying out our method is diagrammatically illustrated in Fig. 1 40 of the accompanying drawing in combination with a gun, whilst Fig. 2 diagrammatically shows the interior of an appurtenant projectile equipped with an electric time fuse.

In the arrangement shown in Fig. 1, the 45 charging and setting of the electric fuse takes place by means of separate excitation by an exciting coil surrounding a section of the path of the projectile. In order to secure 50 this coil against the direct action of the propulsive gases, the latter are preferably deflected laterally between the muzzle and the exciting coil, this being obtained by mounting a muzzle brake *b* on the gun-barrel *a*, which arrangement is of advantage still to 55 obtain other purposes.

The exciting coil *c* is mounted on the cylindrical portion *b*, located in front of the baffle wall *b*, of the muzzle brake, and is connected 60 through a regulating resistance *d* and an ammeter *e* to a source of current *f*. The regulating resistance serves to vary the electromotive force supplied to coil *c* and thus to vary the strength of the field of lines of 65 force generated by said coil. The resistance

may be installed directly at the gun or separately from it at a special stand. A second regulating device *d* may further be provided, as indicated in the embodiment shown, so that the regulation of the strength of the field produced by coil *c* may be effected both at the gun and at a station located at a distance therefrom. 70

The projectile *g* shown in Fig. 2 and intended to be fired by the described gun, possesses a coil *h* arranged on its shell surface closely behind the guide bunch *g*. The ends of this coil *h* are connected to a second coil *i* and to a condenser *k*. An iron core *l* is shiftably mounted in the coil *i*, which core is partly outside the latter under the action of a spring *m*. The iron core has pivotally connected to it a lever *o* which is mounted on one end for rocking motion in the body of the projectile by means of a pivot *n*. This lever is further pivotally connected on its free end with a shiftable rack *p* and abuts in position of rest on a fixed lug *g*, under the action of spring *m* acting on the iron core *l*. The rack *p* has fixed on it a tilting contact piece *q* adapted to interconnect the wires *s* which connect the condenser *k* with the contact pieces *s* embedded in the primer *r*. 85

During transportation and until the projectile is fired, the various parts of the electric projectile fuse assume the positions shown in Fig. 2. When fired the contact *t* which heretofore has been held in open position by means of a spring, not shown, will be moved into the circuit of the condenser *k* to the coil *h* against the operation of a spring. At the moment the coil *h* enters the fields of force produced by the exciting coil *c* in the end of the gun-barrel, an induction current is produced in coil *h*. This flows in part through the ignition coil *i* and the other part through the closing contact *t* to the condenser *k* and places this condenser in a loaded or charged condition. Due to the current flowing in the ignition coil *i* the iron core *l* will be pulled 100 into the coil and thereby presses the spring *m* together and at the same time swings the lever *o* in the direction of the arrow *x*. Thereby the contact piece or member *q* which is secured to the toothed rod *p* strikes an abutment on the projectile body and thereby is rocked out of its heretofore safe position, that is open position, into a position whereby the lower portion, which is constructed as a rigid member, moves into the position above 105 the heretofore open contacts from the condenser *k* to the primer *r* in the circuits *s*, so that upon the return of the toothed rod *p* the circuit will be closed by the bridging of the member *q*. As soon as the ignition coil *h*, during the further flight of the projectile, is through and past the field of the exciting coil *c*, the induction circuit and therewith the magnetic operation of the coil *i* on the core *l* will cease. At the same time, the firing 110

125

130

135

speed has been lowered to such an extent that the contact *t* will be opened again under the action of its spring and the condenser *k* will maintain its charge since it is now disconnected from the coils *i* and *h*. The core *l* will thereby be moved again as heretofore. Under the action of spring *m* the core *l* moves outwardly beyond coil *i*, takes with it the rack *p* and shifts the contact piece *q* toward the 10 contact points of the wires *s*¹ leading from the condenser *k* to the primer *r*. This motion of the rack *p* and of contact piece *q* is retarded by the fact, that now a pair of wings *v* is rotated by rack *p* through the intermediary of a gear *u*. Upon the wiring *s*¹ being closed thereafter by contact piece *q*, the condenser *k* is discharged and a spark is produced between the poles embedded in the primer *r* which is thereby ignited.

20 The strength of the electromotive force produced in the coil *h* and acting in the coil *i* depends on the strength of the field produced by the exciting coil *c* mounted on the gun-barrel. The greater this strength in the exciting coil *c* is, the more the iron core *l* of the fuse is attracted into the magnet coil *i* and the more time passes until the circuit comprising the condenser *k* and the initial ignition *r* is closed after the projectile has passed 25 through the exciting coil *c*.

30 The regulating resistance *d* enclosed in the circuit leading to the exciting coil *c* has a scale which permits to read off the moments of ignition for each adjusted strength of resistance and for each fuse used. This scale may conveniently be arranged on the ammeter *e* interposed in the circuit leading to the exciting coil *c*, so that variations of the current supplied from the source *f* and therefore 35 with variations of the moments of ignition may be seen at once and may be compensated for by inserting more or less resistance, to obtain the desired moment of ignition.

40 What we claim and desire to secure by Letters Patent, is:—

45 1. The method of supplying electric energy to electric projectile fuses carrying with them in an electric storage device a portion of the electric energy required for igniting the primer, consisting in transmitting to the electric igniting device of the projectile the remainder of electric energy required for provoking said action, from a source of current separate from the projectile and after the 50 projectile has been fired.

55 2. The method of supplying electric energy to electric projectile fuses equipped with an electric generator adapted to produce a part of the electric energy required for igniting the primer, consisting in transmitting to the electric igniting device of the projectile the remainder of electric energy required for provoking said action, from a source of current separate from the projectile and after the 60 projectile has been fired.

3. A gun-barrel and a projectile adapted to be fired thereby and having an electric igniting device, and an electric conductor arranged near the path of the projectile and adapted to actuate by induction the igniting device of the projectile passing past it during flight. 70

4. A gun-barrel and a projectile adapted to be fired thereby and having an electric igniting device, and means for producing near the path of the projectile a field of electric lines of force to be crossed by the projectile during its flight, to actuate by induction the igniting device of the projectile. 75

5. A gun-barrel and a projectile adapted to be fired thereby and having an electric igniting device, and means for producing before the muzzle of said gun-barrel a field of electric lines of force adapted to be crossed by said projectile during flight, to actuate by induction the igniting device of the projectile. 80

6. A gun-barrel and a projectile adapted to be fired thereby and having an electric igniting device, and means connected to the muzzle of said gun-barrel and adapted to produce before the muzzle of said gun-barrel a field of electric lines of force adapted to be crossed by said projectile during flight, to actuate by induction the igniting device of the projectile. 85

7. A gun-barrel and a projectile adapted to be fired thereby and having an electric igniting device, an electric conductor arranged near the path of the projectile and adapted to actuate by induction the igniting device of the projectile passing past it during flight, and means for varying the electric energy produced by said conductor, to vary the action of said igniting device. 90

8. A gun-barrel and a projectile adapted to be fired thereby and having an electric time fuse adapted to be actuated differently by electric energy of different strength, means, for producing in the path of the projectile a field of electric lines of force adapted to be crossed by the projectile during flight, to actuate by induction said time fuse, and means for varying the electric energy produced by said field, to vary the timing action 100 of said time fuse. 110

In testimony whereof, we have signed our signatures.
